[57] CLAIM

The ornamental design for a safety belt latch assembly,
as shown.

DESCRIPTION

FIG. 1 is a front elevational view of a safety belt latch assembly showing my new design;

FIG. 2 is a top edge view thereof, the bottom edge
being a mirror image thereof;

FIG. 3 is a left-end view thereof;

FIG. 4 is a right-end view thereof; and

FIG. 5 is a rear elevational view thereof.

FIG. 1

FIG. 2

FIG. 3

FIG. 4
